PREFABRICATED ROOF SLAB

Charles D. Iddings, Jack R. Bechtold, and Paul E. Borg, Tulsa, Okla., assignors to Lee C. Moore Corporation, Pittsburgh, Pa., a corporation of Pennsylvania

Application September 6, 1951, Serial No. 245,328

8 Claims. (Cl. 108—13)

1

This invention relates to prefabricated roof slabs, and more particularly to those used on buildings that are dismantled after a short time and reassembled in another location.

In many industries, such as the oil well drilling industry, there is a need for buildings to be used as shelters for machinery for a short period, such as several weeks, after which they are dismantled and moved to a new location. Obviously, it is desirable to erect such buildings from prefabricated sections that can easily be connected together. One of the more serious problems encountered is concerned with the roofs. Of course the roofs should be watertight, but the temporary nature of their construction makes any form of caulking undesirable.

It is among the objects of this invention to provide prefabricated roof slabs which are of relatively simple and inexpensive construction, which can be quickly assembled to form a watertight roof, which can be connected easily to the roof supports, which require a minimum of connecting members, which can be made in the desired size without regard to the spacing between or the direction of the roof supports, and which are not likely to be damaged during handling or transportation.

In accordance with this invention, each slab comprises a rectangular frame having end members connected by side members that are in the form of angle bars. The bar at one side of the frame has upwardly diverging sides which form a gutter when the roof is laid, and the bar at the opposite side of the frame has downwardly diverging sides to form a hook. The hook bar of each frame is adapted to receive and fit over the outer side of the gutter bar of like frame beside it to connect the frames together. Each frame is covered with suitable sheet material that projects a short distance from one end of each frame to overlap the slab at that end of the frame. Also, one end of each gutter bar may be provided with a short bridging bar that projects into the gutter of the next slab. It is desirable to provide an end member of each slab with outwardly projecting means at its bottom to support the end member of the adjoining slab and to enable the latter to hold down the first end member. An anchor member preferably extends diagonally across a corner of each frame between the inner side of its hook bar and the adjoining end member. This anchor member is adapted to be tied down to a supporting structure to hold the frame in place.

The preferred embodiment of the invention

2

is illustrated in the accompanying drawings in which Fig. 1 is a plan view of a sloping roof formed from our slabs, with parts of some of the slabs broken away; Fig. 2 is an end view of the upper end of the roof; Fig. 3 is a vertical longitudinal section taken on the line II—II of Fig. 1; Fig. 4 is an enlarged plan view of a single slab, with parts of the cover sheet broken away; Fig. 5 is an end view of the slab; and Fig. 6 is an enlarged fragmentary view taken on the line VI—VI of Fig. 1.

Referring to the drawings, a plurality of sloping roof slabs are laid side by side and end to end on a supporting structure which may consist of parallel beams or trusses 1 supported in any suitable manner by the sides of the building (not shown). As shown in Fig. 4, each of the slabs has a rectangular frame that is formed from end members 2 and 3 connected by side members 4 and 5. A central cross member 6 also may be used to reinforce the frame. The side members are angle bars, and the end members likewise may be angle bars with one flange lying in the upper plane of the frame. One side bar 4 has its flanges diverging upward with their upper edges disposed in the plane of the upper flanges of the two end bars, as shown in Figs. 5 and 6. This side bar forms a V-shape rain gutter extending down the sloping roof. In most of the slabs the angle bar 5 at the opposite side of the frame is inverted so that its flanges diverge downward. The inclination of these flanges is the same as that of the gutter bar flanges at the other side of the frame so that the outer flange of the inverted bar can extend down into the gutter bar of the frame beside it and fit flat against the inner surface of the outer flange of the gutter bar. The inverted bar thus forms a hook that hooks onto the adjoining gutter bar. The hook bar 5 preferably has narrower flanges than the gutter bar in order to save weight and expense, and to keep the outer flange of the hook bar from extending below the highest water level to be expected in the gutter so as to avoid any danger of water traveling up between the overlapping flanges by capillary action and thereby leaking through the joint. The top of the hook bar projects above the tops of the adjoining end bars a distance approximately equal to the thickness of the bar material, so that when the different frames are hooked together the tops of the end bars of all of the frames will lie in substantially the same plane, as shown in Fig. 2, and not be tilted relative to one another.

The frames in the row extending along one side of the roof are not provided with hook bars 5. Instead, the place of each hook bar is taken by another gutter bar 8 so that there will be gutters along both sides of the roof.

Welded to the upper end bar 2 of each frame, except the frames along the upper end of the roof, is one or more supports in the form of angles 10 that project outward from the frame below the end bar. As shown in Fig. 3, these supporting angles support the end bar 3 at the lower end of the next higher frame and thereby assure that the tops of adjoining end bars will lie in the same plane. The supporting angles also permit the lower end of each frame to hold down the upper end of the next lower frame.

To prevent water from leaking through the joints formed between abutting gutter bars 4, a short bridge bar 11 is welded in the lower end of each gutter bar and projects a short distance into the upper end of the next lower gutter bar. These bridge bars are made of sheet metal strip bent lengthwise into V-shape to conform to the inside of the gutter bars and to extend part way up their sides. The water flowing down the gutters therefore flows across the joints between the gutter bars through these bridge bars.

The slab frames can be fastened down to the underlying trusses in several different ways, but it is preferred to provide each frame with an anchoring member in the form of a rod 12 that extends diagonally across a lower corner of the frame between its end bar 3 and hook bar 5, to which the rod is welded. A hook bolt 13 is hooked over each rod and is bolted to the underlying truss 1, or to some other rigid member. Only one anchoring member is needed for each of many of the frames, because the opposite end of the frame is held down by the next higher frame resting on angles 10, and the opposite side of the frame is held down by the frame that overlaps that side. Wherever there is a frame that has a corner that is not held down in one of these two ways, an additional diagonal rod and hold-down bolt can be provided. For example, the frames at the right hand side of the roof shown in Fig. 1 need a diagonal rod across their lower right hand corners, while the uppermost frame in that row needs similar rods 16 and 17 across both of its upper corners. The rest of the frames in the upper row each has a rod 16 across its upper left hand corner. Due to the way in which the frames are overlapped and anchored it is not necessary for their end joints to fall over the centers of the trusses, nor for the trusses to extend cross-wise of the roof.

Each frame is covered by sheet material, preferably a corrugated metal sheet 19 which has its corrugations extending lengthwise of the frame. One edge of the sheet extends a short distance into the gutter at one side of the frame and is riveted or spot welded to the gutter bar 4. The opposite side of the sheet overlaps the hook bar 5 and is fastened to its outer flange in like manner. The upper end of the sheet preferably terminates on top of the upper end bar 2, but its lower end projects beyond the lower end bar 3 a distance equal to the distance that the adjacent bridge bar 11 projects beyond the frame. Consequently, the lower end of each sheet overlaps the upper end of the next lower slab so that water will not leak between the ends of the sheets.

These slabs can be laid quickly and easily to form a roof, especially since only one bolt is used for anchoring many of them. The joints

are watertight without caulking, and rain gutters are built into the roof. As the covering sheets of the slabs project from the frames only at one end, there is little likelihood of the projecting portions being damaged while the slabs are being handled or transported from one location to another.

According to the provisions of the patent statutes, we have explained the principle of our invention and have illustrated and described what we now consider to represent its best embodiment. However, we desire to have it understood that, within the scope of the appended claims, the invention may be practiced otherwise than as specifically illustrated and described.

We claim:

1. A plurality of prefabricated roof slabs adapted to be laid with overlapping sides, each slab comprising a rectangular frame having end members connected by side members in the form of angle bars, the bar at one side of the frame having upwardly diverging sides forming a gutter and the bar at the opposite side of the frame having downwardly diverging sides forming a hook, and sheet material covering the frame and fastened thereto, the hook bar of each slab being adapted to receive and fit over the outer side of the gutter bar of an adjoining slab to connect the slabs together.

2. A plurality of prefabricated roof slabs adapted to be laid with overlapping sides, each slab comprising a rectangular frame having end members connected by side members in the form of angle bars, the bar at one side of the frame having upwardly diverging sides forming a gutter and the bar at the opposite side of the frame having downwardly diverging sides forming a hook, sheet material covering the frame and fastened thereto, and an anchoring member extending diagonally across a corner of the frame between the inner side of its hook bar and the adjoining end member, the hook bar of each slab being adapted to receive and fit over the outer side of the gutter bar of an adjoining slab to connect the slabs together, and the anchoring members being adapted to be tied down to a supporting structure to hold the slabs in place.

3. A plurality of prefabricated roof slabs adapted to be laid with overlapping sides, each slab comprising a rectangular frame having end members connected by side members in the form of angle bars, the bar at one side of the frame having upwardly diverging sides forming a gutter and the bar at the opposite side of the frame having downwardly diverging sides forming a hook, and sheet material covering the frame and fastened to the inner side of its gutter bar and the outer side of its hook bar, the hook bar of each slab being adapted to receive and fit over the outer side of the gutter bar of an adjoining slab to connect the slabs together.

4. A plurality of prefabricated roof slabs adapted to be laid with overlapping sides, each slab comprising a rectangular frame having end members connected by side members in the form of angle bars, the bar at one side of the frame having upwardly diverging sides forming a gutter and the bar at the opposite side of the frame having downwardly diverging sides forming a hook, the top of the gutter bar being disposed in substantially the same plane as the tops of said end members, the top of the hook bar being disposed above said plane a short distance, and sheet material covering the frame and fastened to the side bars thereof, the hook bar of each slab being

adapted to receive and fit over the outer side of the gutter bar of an adjoining slab to connect the slabs together.

5. A plurality of prefabricated roof slabs adapted to be laid with overlapping sides and ends, each slab comprising a rectangular frame having end members connected by side members in the form of angle bars, the bar at one side of the frame having upwardly diverging sides forming a gutter and the bar at the opposite side of the frame having downwardly diverging sides forming a hook, and sheet material covering the frame and fastened to the side bars thereof, the hook bar of each slab being adapted to receive and fit over the outer side of the gutter bar of an adjoining slab to connect the slabs together, said sheet material projecting from only one end of each frame to overlap a short distance the slab at that end of the frame.

6. A plurality of prefabricated roof slabs adapted to be laid in rows with overlapping sides, each slab comprising a rectangular frame having end members connected by side members in the form of angle bars, the bar at one side of the frame having upwardly diverging sides forming a gutter and the bar at the opposite side of the frame having downwardly diverging sides forming a hook, sheet material covering the frame and fastened thereto, and a short bridge bar having upwardly diverging sides fitting rigidly in one end of the gutter bar and projecting therefrom to fit in the end of the gutter bar of the frame adjoining that end of the first gutter bar, the hook bar of each slab being adapted to receive and fit over the outer side of the gutter bar of an adjoining slab to connect the slabs together.

7. A plurality of roof slabs adapted to be laid in rows with overlapping sides, each slab comprising a rectangular frame having end members connected by side members in the form of angle bars, the bar at one side of the frame having upwardly diverging sides forming a gutter and the bar at the opposite side of the

frame having downwardly diverging sides forming a hook, sheet material covering the frame and fastened thereto, and rigid means projecting a short distance lengthwise of the frame from one of said end members for supporting the end member of an adjoining frame, the hook bar of each slab being adapted to receive and fit over the outer side of the gutter bar of an adjoining slab to connect the slabs together.

10 8. A plurality of prefabricated roof slabs adapted to be laid with overlapping sides and ends, each slab comprising a rectangular frame having end members connected by side members in the form of angle bars, the bar at one side of the frame having upwardly diverging sides forming a gutter and the bar at the opposite side of the frame having downwardly diverging sides forming a hook, rigid means projecting a short distance lengthwise of the frame from the bottom of one of its end members for supporting the end member of an adjoining frame, an anchoring member extending diagonally across a corner of the frame between its other end member and the inner side of its hook bar, the hook bar of each frame being adapted to receive and fit over the outer side of the gutter bar of an adjoining frame to connect the frames together, the anchoring members being adapted to be attached to a supporting structure to hold the frames in place, and sheet material covering the frame and fastened to the side bars thereof, said material projecting from only one end of each frame to overlap a short distance the slab at that end of the frame.
